[57] CLAIM

The ornamental design for a microwaveable chip and dip server, as shown and described.

DESCRIPTION

FIG. 1 is a perspective view of a microwaveable chip and dip server of the present invention;

FIG. 2 is a side elevational view of the microwaveable chip and dip server of FIG. 1, with the opposite side elevational view being identical;

FIG. 3 is a plan view of the microwaveable chip and dip server of FIG. 1;

FIG. 4 is a side elevational view of the microwaveable chip and dip server of FIG. 1 taken ninety degrees away from the view of FIG. 2, with the opposite side elevational view being identical; and,

FIG. 5 is a bottom view of the microwaveable chip and dip server of FIG. 1.
